TRUSS

Moris Portnow, New York, N. Y.

Application June 11, 1938, Serial No. 213,121

1 Claim. (Cl. 128—102)

This invention relates to trusses and more particularly to an improved form thereof, adapted to be rigidly fitted to the bodies of patients having wide variations in girth, anatomical frame and types of hernia.

Generally speaking, two types of trusses are now commonly in use. One type has as one of its elements a sectional band made entirely of metal, and the other type embodies a band composed of an elastic material.

The obvious disadvantage of the first named type of truss is, that it is entirely inelastic, hence extremely uncomfortable, while the latter permits of excessive elasticity, which is contrary to the purpose for which the device is intended.

With these matters in mind, it is the principal object of this invention to provide a truss having cushion pads connected each to a sectional metal band so as to confer on the truss a flexibility and elasticity within certain predetermined limits, and adjustable to positively define such limits.

A further feature is in the provision of a truss in which no metal parts make contact with the wearer, and which can be applied and removed without difficulty, whenever desired.

Another aim is to produce a truss of novel and highly practical construction which, due to its adjustable flexible and elastic features, may be worn with unusual ease and safety.

A still further advantage lies in the production of a truss of this character which, once adjusted to a wearer's requirements, needs no further adjustment, and which, because of its controlled flexibility, will enable the cushioned pads always to make contact with precisely the same part of the wearer's body, no matter how often the truss is removed and applied.

These beneficial objects, together with others which will hereinafter appear, are accomplished by the novel construction and combination of simple parts, hereinafter described and illustrated in the accompanying drawing, forming a material component of this disclosure, and in which:

Figure 1 is a perspective view of an embodiment of the invention, showing the truss in extended or operative position, the truss being viewed from the front.

Figure 2 is a similar view, looking from the rear, parts being omitted.

Figure 3 is a top plan view of the truss, in a loose or inoperative position, indicating the loose straps in the rear thereof; and

Figures 4, 5, 6 and 7 are respectively sectional

views taken on the lines 4—4, 5—5, 6—6 and 7—7 of Figure 3.

Referring in greater detail to the drawing, the numeral 15 designates in general a pair of opposed contact pads, filled with selected cushioning material and covered with suitable fabric.

These pads are preferably pear-shaped in profile, having firmly secured in them the outer ends of two side embracing flat metal members 16—17 disposed under flexible covers 18—19 secured on the outer end portions of elastic straps 20—21 extending between the pads in overlapping relation, their rear extremities being bound by flexible clips 22—23, the latter members constituting liaison members for affixing the truss to the body.

The straps 20—21 are of woven fabric having double walls of elastic threads, the inner layer 20 having, adjacent its outer end clip 23, a permanently secured flattened loop 24 to which is attached a non-stretchable strap 25 provided with a series of eyelets 26 disposed in spaced longitudinal relation and extending nearly to the pad.

Secured on the face of the strap 21, near the clip 22, is a patch 27 engaging one of the elements of a flattened ring 28 through which passes 25 the bight of an elastic strap, the doubled under portion 29 being firmly fixed to the strap 20 near the rear end of the spring cover 18.

The outer layer 30 of the inelastic strap engages a buckle 31, secured to the element 29, thereafter passing under a keeper bar 32 and extending in the manner of a loose tongue 33.

Fixed on the face of the spring cover 16 is a button head stud 35 adapted to be adjustably engaged in any of the eyelets 26, thereby essentially modifying the operative length of the truss band as a unit, which is further adjustable by the buckle 31.

It will be noted that the inner section 20 of the belt has attached to it a buckle 31 and loop 24, the latter with its connection 25 passing under the keeper 36 and having the eyelets 26, while that portion between the buckle and the loop is elastic and subject to stretch within the limits of the patch 27 and the buckle 31 which is easily adjustable, while the ultimate length is adjustable by selective engagement of the stud 35 in the eyelets 26.

It will thus be seen that I have provided a truss which is adapted to be snugly fitted to the body and yet so endowed that it can be fitted on patients having wide variations in girth, anatomical frame and types of hernia.

In affixing the truss to the body, the truss is initially loosely applied thereto and then the

liaison or strap members taken up the required amounts, so as to securely and effectively position the truss. As will be seen from the drawing and the appended claim, the truss comprises two 5 metallically re-enforced side embracing portions 20—21 which are adaptable for adjustable connection to each other at the side and rear there- or by means of the liaison members 25—30, the 10 terminal ends of said metallically re-enforced portions carrying the usual hernia pads.

In fitting the truss to the body of the wearer, the strap 20 is unhooked from the stud 35 and the loop 24 is moved rearwardly along the portion 21 as far as it will go or as far as necessary. The 15 strap 30 is let out as far as possible or necessary so that the truss can be loosely placed around the body of the wearer. When the hernia pads are placed in position, the loop 24 is moved rear- 20 wardly along the truss portion 21 until the desired tension between the two truss portions is obtained. The eyeleted strap 25 is then hooked on the stud 35 at the appropriate eyelet and thence the strap 10 is properly adjusted.

As changes can be made within the scope of 25 the invention, it is intended that all matter contained in the foregoing description or shown in

the accompanying drawing shall be interpreted as illustrative and not as limitative of the invention.

Having thus described the invention, what is claimed as new and sought to secure by Letters 5 Patent, is:

A truss comprising two spaced apart pear-shaped cushion pads, an arcuately curved metallic spring fixed in the smaller end of each pad to encompass the sides and portion of the front 10 and back of a body, a flattened tubular casing completely enveloping said springs and attached at its ends to said pads, said casing being elastic and of woven material, flexible covers secured over said casing at the regions occupied by said 15 springs and attached at their front ends to said pads, a strap fixed at one end to one of said covers and the underlying casing at the rear portion thereof to extend towards the front, means to guide said strap, and means to retain the opera- 20 tive length of said strap in selective adjustment, whereby that part of said casing between the adjacently spaced ends of said springs may be modified in length together with the distance between the springs to fit the body.

MORIS PORTNOW.
